UNITED STATES PATENT OFFICE.

EDWARD F. SMITH, OF CINCINNATI, OHIO, ASSIGNOR TO THE SMITH ELECTRIC TOOL CO., OF CINCINNATI, OHIO, A CORPORATION OF OHIO.

MEANS TO CONTROL MAGNETIC CIRCULATION IN ELECTRIC-CURRENT-PRODUCING DEVICES.

1,044,827.

Specification of Letters Patent.

Patented Nov. 19, 1912.

Application filed October 1, 1910. Serial No. 584,810.

To all whom it may concern:

Be it known that I, EDWARD F. SMITH, a citizen of the United States, and residing at Cincinnati, Hamilton county, State of Ohio, have invented certain new and useful Means to Control Magnetic Circulation in Electric-Current-Producing Devices; and I do declare the following to be a clear, full, and exact description of the invention, attention being called to the drawing which accompanies this application and forms a part thereof.

As is well known in an electric motor, operated by a dynamo-current there is also generated an electro-motive force which counteracts the incoming dynamo-current whereby the motor is operated. The voltage of this counter electro-motive force is directly proportional to the density of the magnetic field through which the armature of the motor rotates, or as it may also be stated, to the number of lines of force contained in the magnetic circulation which prevails between complementary poles. It is also known that the voltage of this counter-electromotive force and the consequent speed of the armature may be controlled and regulated by control and regulation of the intensity of volume of this magnetic field.

This condition may be taken advantage of for the purpose of regulating the speed of motors used to operate tools as for instance drills and grinders directly connected to the armature shaft and my invention relates to certain new and useful means whereby in a motor so used the magnetic circulation is regulated and controlled for the purpose of regulating and controlling correspondingly the capacity of the motor to generate this counter electro-motive force and in consequence thereof the rotary speed of its armature, which is influenced by said magnetic circulation.

In the following specification and particularly pointed out in the claims at the end thereof, will be found a full description of my invention, together with its operation, parts and construction, which latter is also illustrated in the accompanying drawing, in which:

Figure 1, shows in cross-section a motor-housing, constructed for use in connection with a tool to be electrically operated, the

housing being provided with the speed-controlling means contemplated by my invention. Fig. 2, in a similar view shows these means in a different position. Fig. 3, shows in a similar view my invention applied to a multipolar motor. Fig. 4, shows a portion of such a motor-housing enlarged and illustrates a certain feature of construction of my device.

In the drawing, A indicates the motor-housing formed by an annular, hollow casting, and B indicates field-magnet-cores forming projections on the inner side of said housing and of which there may be one or more. The heavy dotted lines shown across said cores are intended to represent the wire-coils of the field-magnets, or the space occupied by said coils.

C indicates the armature mounted on shaft c.

Ordinarily, magnetic circulation proceeds as indicated by the arrows shown in connection with the light dotted lines in Fig. 1, passing from one pole b across and through the rotary path of the armature, to another pole and through part of the housing between said poles, said part of the housing constituting the yoke between the poles, and being indicated by letter a. Obviously the volume of this magnetic circulation depends on the size or capacity of the conduit which affords passage for it and is represented by the size or area of the yoke taken in a plane transversely to the direction in which the magnetic currents move. Consequently, by changing the size of this area within certain limits, the volume of the magnetic flux or the lines of force available for co-action with the armature are proportionately affected, which effect necessarily extends to the current-producing capacity of the motor and to the speed of its armature. The means whereby I attain these effects are constructed as follows: The thickness of at least one of those parts of the housing where it forms a yoke, and by preference the thickness of all these yoke-forming parts is reduced to form recesses d as shown in all the figures of the drawing, said recesses being elongated and provided on the inside of the yoke parallel to the axis of housing and armature and may extend through the entire length of the same. Into each of these recesses I fit a complementary yoke-section

D, which is adjustably supported so that it may occupy a normal position in which it is entirely within said recesses as shown in Figs. 1 and 4 and completes with the adjacent and contiguous parts of the yoke the normal and largest cross-sectional area of the same available to carry magnetic circulation. From this position it may be adjusted to a position shown in Fig. 2, in which it forms no part of this cross-sectional area of the yoke and whereby the area available to carry magnetic flux is limited to the reduced part of the yoke, this being the reduced thickness of the metal of the housing remaining outside of the deepest part of the recesses. Means are provided to move yoke-sections D to positions intermediate these two extreme positions and each of which positions affects the rotation of the armature to a proportionate degree.

In Figs. 1, 2, 3, and 4, recess d is substantially semi-circular and the yoke-section is correspondingly shaped. In this case this latter may be supported by trunnion-journals 10, which find bearings in opposite ends of the housing. An arm 11 is provided, it may connect to one of the trunnions, or to section D direct, in which latter case it reaches the same through a slot in the housing. By means of this arm, section D may be moved to various positions, each providing accordingly different changes of speed in the armature. Means to positively hold the adjustable yoke sections in adjusted positions may be dispensed with, since the magnetic attraction is sufficient for this purpose. Where a number of yoke-sections are provided as shown in Fig. 3, these arms 11 may all be connected for simultaneous manipulation as for instance by a ring 12, suitably mounted.

While as shown, the magnetic circuit is controlled by the adjustment of the size of the area of its conduit, I amplify this control as shown in Figs. 1 to 3 by diverting the magnetic circuit from its normal passage through the rotary path of the armature. This I do by projecting parts of an auxiliary member (yoke-section D) into the space between two complementary poles whereby this projected part, for the time being, forms an auxiliary and additional pole as best shown in Fig. 2, whereby the magnetic circuit is shunted out of its normal path and short circuited, a substitute circuit being set up as shown by the dotted lines in Fig. 2.

The manipulation for adjusting the position of yoke-section D, may be a positive one in either direction, or it may be positive in one direction only and automatic for the purpose of returning it to its normal position. In the latter case a spring 14 of proper strength is used to return the yoke-sections to normal condition, it may be ar-

ranged as shown in Fig. 4, where it occupies a recess between the yoke and the yoke-section, one end of it being connected to the yoke and the other to the yoke-section. In this case, as soon as the switch which controls the feed circuit to the motor is turned off, consequent cessation of the magnetic attraction which held the yoke-section in adjusted position, enables the spring to return the yoke-section to normal position, which means normal speed conditions of the armature. Accidents are thus avoided, as for instance when the motor is started up with parts left in a position previously adjusted for a certain speed and which speed for a tool about to be connected would be unsuited. The features of the invention are likewise applicable to generators or dynamos.

I am aware that complementary yoke-sections have been used in connection with yokes and where these sections are fitted to occupy a space between the opposite ends of a completely divided housing, I consider such a construction objectionable inasmuch as it reduces the structural strength of the housing and complicates the construction and fitting thereof. It will be noted that in my construction this objection is absent and rigidity of the structure is preserved by an integral yoke-portion, the object of the invention being attained by merely reducing the thickness of the metal of this yoke portion. I am also aware that such current-control has been attempted by means provided on the outside of the motor-housing and occupying recesses in the magnet-cores. This construction is objectionable for the reason that it is difficult to move the devices, to be moved for adjustment, out of their normal positions, because such movement is resisted by the magnetic attraction which is highest at the particular point where these devices are located in the recesses of the cores. It is furthermore objectionable because available only where the width of the magnet-cores is sufficiently large to permit recessing. It cannot be readily used on cylindrical cores and not at all when such cylindrical cores are of small diameter like on some arc-light machines. It is entirely excluded where cores are built up of laminee or plates, which is generally the case now on large motors, since there the recesses would cut out the bolts whereby said plates are held together. It is also more difficult to support or attach such a motor-housing recessed on its outside, it also takes up more room, by reason of these devices located on the outside of it and the outwardly open recesses are exposed to dust and grit.

Having described my invention, I claim as new:

1. In means for controlling the magnetic circulation in a motor constructed to be

adapted for operation of a tool, the combination of an annular housing containing complementary poles and part of which housing constitutes a yoke through which the magnetic circulation passes and which part between these complementary poles is reduced in thickness to form an elongated recess parallel to the axis of the housing and open on the inner side thereof, a complementary yoke-section fitted to this recess and means to adjust the position of this section, to graduate the area of the yoke through which the magnetic circuit passes.

2. In means for controlling the magnetic circulation in a motor constructed to be adapted for operation of a tool, the combination of an annular housing containing complementary poles and part of which housing constitutes a yoke through which the magnetic circulation passes and which part between these complementary poles is reduced in thickness to form an elongated recess parallel to the axis of the housing and open on the inner side thereof, a complementary yoke-section fitted to this recess and means to adjust the position of this section so that it is either entirely within said recess or only in part so whereby the area of the yoke through which the magnetic circuit passes is accordingly modified.

3. In means for controlling the magnetic circulation in a motor constructed to be adapted for operation of a tool, the combination of an annular housing containing field-magnet cores adapted to constitute complementary magnetic poles, and a yoke-member supported adjustably on the housing between complementary poles and in a manner permitting it to be adjusted to enter into the space surrounded by the housing and between complementary poles so as to attract the magnetic circuit between these poles and to shunt it from its normal path.

4. In means for controlling the magnetic circulation in a motor constructed to be adapted for operation of a tool, the combination of an annular housing containing field-magnet cores adapted to constitute complementary magnetic poles and part of which housing between these cores constitutes a yoke through which the magnetic circulation passes and which part on the inside of the housing is reduced in thickness to form an elongated recess between these poles and parallel to the axis of the housing, a complementary housing-section fitted to this recess and means to adjust the position of this section to supplement or to reduce the area of that part of the housing and to also cause said section to project into the space between complementary poles, to attract the magnetic circuit from its normal path and to set up a shunt-circulation between it and one of the poles.

5. In means for controlling the magnetic circulation in a motor constructed to be adapted for operation of a tool, the combination of an annular housing, part of which constitutes a yoke through which the magnetic circulation passes and which part is reduced in thickness to form an elongated recess parallel to the axis of the housing, a complementary yoke-section fitted to this recess and adapted to entirely close the same, means to adjust the position of this section to graduate the area of the yoke through which the magnetic circuit passes and means to return this yoke-section automatically to its normal position.

In testimony whereof, I hereunto affix my signature in the presence of two witnesses.

EDWARD F. SMITH.
